CLAIM

The ornamental design for a golf map marker, as shown and described.

DESCRIPTION

FIG. 1 is a front elevational view of a golf map marker showing my new design;

FIG. 2 is a front elevational view drawn to an enlarged scale;

FIG. 3 is a right side elevational view of FIG. 2, the left side being a mirror image thereof;

FIG. 4 is a top plan view of FIG. 2; and,

FIG. 5 is a bottom plan view of FIG. 2.

The rear of the article is plain and unornamented.

FIG. 1

FIG. 3

FIG. 2

FIG. 4

FIG. 5
